UNITED STATES PATENT OFFICE

129,536

DESIGN FOR A LAUNDRY TRAY COVER

Ralph M. Moon and Irene Moon, Los Angeles, Calif.

Application November 12, 1940, Serial No. 96,473

Term of patent 7 years

To all whom it may concern:

Be it known that we, Ralph M. Moon and Irene Moon, citizens of the United States and residents of the city of Los Angeles, in the county of Los Angeles and State of California, have invented a new, original, and ornamental Design for a Laundry Tray Cover, of which the following is a specification, reference being had to the accompanying drawing, forming part thereof.

In the drawing:

Fig. 1 is a perspective view of a laundry tray cover showing our new design.

Fig. 2 is a bottom plan view.

Fig. 3 is a section taken along the line 3—3 of Fig. 2.

Fig. 4 is a section taken along the line 4—4 of Fig. 2.

We claim:

The ornamental design for a laundry tray cover, substantially as shown.

RALPH M. MOON.
IRENE MOON.
